CARBURETOR

Vito Campanella, New York, N. Y.

Application July 18, 1935, Serial No. 31,981

2 Claims. (Cl. 261—44)

This invention relates to improvements in carburetors for internal combustion engines.

One of the many objects of the invention resides in a carburetor for use upon internal combustion engines having either the updraft or down draft system of fuel feed, and which embodies features of construction for increasing the efficiency of fuel consumption, by proportionately increasing the flow of air and liquid fuel to the mixing chamber.

Another feature of the invention is to provide a carburetor in which the liquid fuel supply from the reservoir may be manually controlled from the dash board of a motor vehicle to adjust the same to suit various climatic and engine running temperatures, for under certain temperature conditions a lean or rich mixture of air and liquid fuel is desired for efficient and economic operation.

A further object of the invention is the provision of a carburetor in which the flow of air to the mixing chamber is proportionate to the suction of the pistons of the engine and wherein the air flow may be manually regulated from the dash board to accurately vary the flow to meet changes in climatic temperatures.

A still further object resides in a carburetor having the above mentioned features which all coact to induce quicker and positive starting of an internal combustion engine.

With these and other objects in view, the invention resides in the certain novel construction, combination and arrangement of parts, the essential features of which are hereinafter more fully described, are particularly pointed out in the appended claims and are illustrated in the accompanying drawings, in which:

Figure 1 is a side elevational view of my improved carburetor.

Figure 2 is a horizontal sectional view on the line 2—2 of Figure 1.

Figure 3 is an enlarged detail horizontal sectional view illustrating the adjusting means for the liquid fuel supply.

Figure 4 is a vertical longitudinal sectional view through the carburetor.

Figure 5 is an enlarged detail vertical sectional view with the fuel regulating valve in elevation.

Figure 6 is an enlarged vertical sectional view through the fuel regulating valve.

Figure 7 is a detail sectional view through a dash-board illustrating the holding means for the regulating rods.

Referring to the drawings by reference characters, the numeral 10 designates my improved carburetor in its entirety and which includes a horizontally disposed pipe section 11, the air inlet end of which is provided with a threaded nipple 12 while the opposite end is down turned and provided with a flange 13 for coupling with the intake manifold of an internal combustion engine.

The intermediate portion of the pipe section 11 is enlarged and provided with a well 14 which opens through the top of the pipe section. Seated in the well 14 is a block 15 having a substantially U-shaped passage 16 formed by a downwardly depending cone bearing or seat 17. The passage 16 communicates with the inlet and outlet end of the pipe section 11 and constitutes a mixing chamber for the liquid fuel and air for the vaporization of the liquid fuel.

The member 15 is held in fixed position by base plate sections 18 which overlap the top of the member 15 and are bolted in position by bolts 19, certain of which pass through one of the base sections 18 and directly into the member 15.

Rising upwardly from the base plate sections 18 are studs 20, which are connected to legs 21 extending downwardly from a liquid fuel reservoir 22. The studs 20 and aligned legs 21 are joined by coupling nuts 23.

Contained within the reservoir 22 is the usual float valve 24, float actuated valve mechanism 25 for controlling the flow of liquid fuel to the reservoir 22 from the fuel supply pipe 26. The reservoir 22 is provided with a fuel outlet 27 and connected to the outlet by a coupling nut or union 28, is the upper flanged end of a rotary valve member 29. The valve member 29 is hollow and the lower end terminates in a cone 30 which is seated in the cone shaped bearing 17 above mentioned, while the upper end is mounted in roller bearings. The valve member 29 adjacent the pointed end of the cone is provided with a restricted fuel feed chamber 31 which is substantially diamond shaped in cross section as shown clearly in Figure 6 of the drawings and forms a part of the fuel supply conduit from the reservoir to the mixing chamber. Liquid fuel enters the chamber 31 through a restricted inlet 32 and is discharged therefrom through radially extending orifices 33 which are upwardly and outwardly inclined. The upper end of the rotary valve member 29 beyond the plane of the base plate 18 is provided with a gear 34 which meshes with a gear segment 35 pivotally mounted as at 36 to one of the base plate sections 18. The gear segment 35 constitutes the actuating gear for imparting turning movement to the rotary valve member and a spring 37 acts to normally hold the gear 35 in a position so that the openings 33 are in register with the orifices 38 provided in the conical valve seat or bearing 17.

The gear segment 35 is provided with an arm 39 to which one end of an actuating rod 40 is operatively connected, the other end of the rod being provided with a manipulating handle 41, the rod being mounted in a bearing member 42 for mounting in the dash board of a vehicle. By the actuation of the rod 40, the gear segment 35 may be turned to impart corresponding turning move-

ment to the rotary valve to vary the radial position of the discharge orifices 33 with respect to the discharge openings 38.

Having explained the construction and means 5 for feeding liquid fuel from the reservoir 22 to the mixing chamber 16, I shall now explain the manner in which air is passed through the mixing chamber for vaporization with the liquid fuel. However, before going into this explanation, it 10 will be seen by reference to Figures 5 and 6 that a guard or apron member 43 is threaded to the cone seat 17 and surrounds the outer ends of the openings or jets 38 for the purpose of deflecting the liquid fuel downwardly for mixture with the air as it passes through the mixing chamber 16.

Threaded to the nipple 12 of the horizontal pipe section 11 is the elbow end 44 of a vertical up-standing pipe section 45, and threaded to the upper end of the pipe section 45 is an angular pipe section 46, the inlet end of which is closed by a screen 47 for filtering air drawn thereto. Pivoted in the section 46 adjacent the inlet end, is a gravity actuated valve 48 which opens by reason of the suction caused by the intake stroke of the 20 pistons of an internal combustion engine.

Rotatably mounted in the pipe section 45 is a rotary fan 49 which may be mounted in anti-friction bearings and extending through the upper pipe section 46 and terminating above and adjacent the blades of the fan at an angle thereto, are air inlet tubes 50, the outer ends 51 being funnel shaped. Although the screened end of the pipe section 46 constitutes the air inlet, a proportionate amount of air is sucked in through the tubes 30 50 depending upon the acceleration of the engine with which the carburetor is associated.

The rotary fan 49 assists in the mixing of the air with the fuel, and furthermore tends to overcome the pulsations in the flow of the air; that is, 40 a momentary rush of air will impart a rotary motion to the fan and its initial inertia will keep it rotated during a momentary slowing up of the flow of air and during this time the fan acts as an impeller.

45 For the purpose of regulating the flow of air through the carburetor, a valve 52 is pivoted in the elbow 44 of the pipe section 45. This valve is normally held in a position to close the air passage by equalizing springs 53 but a restricted passage 50 54 is provided in the valve for permitting a restricted amount of air to pass to the mixing chamber, although upon acceleration of the engine, the suction will move the valve 52 toward the right and provide an enlarged passage for the 55 free flow of air to the mixing chamber. From the above description it will be seen that the speed of the engine controls the inflow of air to the mixing chamber 16 and the flow of liquid fuel to the mixing chamber may be controlled or set by the actuation of the rod 40 to impart rotation to the rotary valve member 29.

For regulating the flow of air irrespective of the automatic valve 48 and valve 52, there is provided a butterfly valve 55 in the inlet side of the 60 pipe section 11. By reference to Figure 1, it will be seen that a coil spring 56 tends to normally hold the butterfly valve in a horizontal or open position but actuation of the valve from the dash board is possible by reason of a rod 57 operatively connected to the butterfly valve exteriorly of the pipe section 11. The rod 57 extends to the dash board of a motor vehicle and is provided with a

knob 58 which when pulled tends to close the butterfly valve against the action of the spring 56.

In Figure 7 of the drawings, I have illustrated a resilient adjustment for the holding of the actuating rods 40 and 57 in an adjusted position. 5 Both rods are held in a similar manner, so that a description of the holding means for the rod 40 will suffice for the holding means for the rod 57.

The rod 40 extends through a bushing 60 10 mounted in the dash board 61 of an automobile. An inner wall of the bushing is provided with a series of undulations or teeth 62 with which the outer rounded end 63 of a pin 64 engages. The pin is slidably carried by the rod 40 and urged 15 outwardly by a spring 65. The tension of the spring is sufficient to hold the pin in seated position between two adjacent humps or teeth, and will yield inwardly upon manual pulling or pushing 20 of the rod to adjusted position.

A butterfly valve 59 is also provided in the pipe section 11 on the outlet side of the mixing chamber for the purpose of controlling the flow of vaporized fuel from the carburetor to the intake manifold.

While I have shown and described what I consider to be the most practical embodiment of my invention, it will be understood that various changes in construction as come within the scope of the appended claims may be resorted to if desired.

Having thus described the invention, what I claim as new and desire to secure by Letters Patent of the United States, is:—

1. A carburetor comprising in combination a 35 mixing chamber, a fuel reservoir mounted above said mixing chamber and having an outlet, a valve seat extending within said mixing chamber and having apertures extending through the walls thereof into said mixing chamber, a hollow 40 valve member rotatably connected to the outlet of said reservoir and seated upon said valve seat, said valve member having outlet apertures therein for register with the first mentioned apertures to establish communication between said 45 reservoir and said mixing chamber and for movement out of registration therewith, and manual actuating means for imparting turning movements to said valve member.

2. A carburetor comprising in combination, a 50 conduit having an air inlet at one end and a mixing chamber intermediate the ends thereof, a fuel supply reservoir mounted on said conduit and disposed above said mixing chamber, said reservoir having an outlet, a hollow valve member rotatably connected at its top end to said outlet and having a cone shaped lower end, a cone shaped seat provided in a wall of said mixing chamber, for receiving the cone shaped end of said valve member, the walls of said seat having 60 passages therethrough communicating with said mixing chamber, an auxiliary fuel feed reservoir in the cone shaped end of said valve member, and fuel outlet ducts in the cone end of said valve member for radial registration with the passages 65 in the walls of said valve seat, and actuating means for imparting a turning movement to said valve member for varying the relative radial position of said outlet ducts with respect to said 70 passages.

VITO CAMPANELLA.
